PORTABLE RADIO

Jean Otis Reinecke, Oak Park, Ill., assignor to
Motorola, Inc., Chicago, Ill., a corporation of
Illinois

Application May 21, 1953, Serial No. 25,135

Term of patent 7 years

(Cl. D56—4)

To all whom it may concern:

Be it known that I, Jean Otis Reinecke, residing in the city of Oak Park, county of Cook, State of Illinois, have invented a new, original, and ornamental Design for a Portable Radio, of which the following is the specification, reference being had to the accompanying drawing, forming a part thereof in which:

Figure 1 is a perspective view of a portable radio showing my new design;

Figure 2 is a side elevational view thereof; and
Figure 3 is a top plan view thereof.

The hidden side of Figure 2 is similar to the side illustrated and the back of the radio is plain.

I claim:

The ornamental design for a portable radio, substantially as shown and described.

JEAN OTIS REINECKE.
